UNITED STATES PATENT OFFICE.

WILLIAM KELSO, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-CENTERING MECHANISM.

1,214,318.

Specification of Letters Patent. Patented Jan. 30, 1917.

Application filed August 17, 1916. Serial No. 115,470.

To all whom it may concern:

Be it known that I, WILLIAM KELSO, a citizen of the United States, residing at Pittsburgh, in the county of Allegheny and State of Pennsylvania, have invented certain new and useful Improvements in Coupling-Centering Mechanism; and I do hereby declare the following to be a full, clear, and exact description of the invention, such as will enable others skilled in the art to which it appertains to make and use the same.

My invention relates to that class of car couplers which are mounted upon railway cars so as to be capable of swinging laterally when the cars to which they are attached pass around a curve.

The principal object of the invention is to provide simple and efficient means whereby the trainman while standing at the side of the car may shift the coupler laterally in either direction so as to move it to proper position for coupling with the coupler of an adjacent car.

A further object of the invention is to so form and combine the elements of the mechanism that it may serve to unlock the coupler.

Generally stated, the means by which these objects are accomplished involve a lever having a plurality of fulcrum points either of which is adapted to coöperate with a fulcrum member mounted upon the car body, the lever being operatively connected to the laterally shiftable car coupler by means of a rod or bar which is connected to the locking mechanism of the coupler so as to be capable of effecting an unlocking movement of the latter.

It is to be understood that the details of construction of the car coupler illustrated in the drawings, although representing a preferred form, are not essential features of the invention in its broad aspect, since the invention is generally applicable to couplers designed to have a lateral movement with respect to the cars upon which they are mounted.

There are other features of invention, involving particular combinations and special features of construction, as will hereinafter appear.

In the drawings illustrating the preferred embodiment of my invention, the scope whereof is pointed out in the claims,

Figure 1 is a front elevation of a laterally movable coupler and devices embodying my invention. Fig. 2 is a detail view, partly in elevation and partly in section, showing portions of the mechanism illustrated in Fig. 1. Fig. 3 is a section on the line 3—3, Fig. 1. Fig. 4 is a detail section on the line 4—4, Fig. 3. Fig. 5 is a detail view illustrating the relation of the operating lever and its fulcrum, the lever being shown in full lines in the position it occupies when the coupler is shifted in one direction and being shown in dotted lines in the position it occupies when the coupler is shifted laterally in the opposite direction.

In the drawings, 1 indicates a coupler having a knuckle 2 and a vertically movable lock 3 for retaining the knuckle in locked position. The coupler is of a well-known type that is mounted upon a railway car so as to be capable of shifting laterally with respect thereto. The lock 3 is capable of being moved to unlocked position by means of a pivoted lock-actuating member 4 whose outer end enters a slot or opening in the lower end of the lock and whose inner end is provided with pintles 5 which are seated in bearings formed in a bracket 6 secured to the coupler so as to be movable therewith. At its rear end the pivoted lock-actuating member 4 is provided with a pocket or recess 7 which is adapted to receive the upwardly extending inner ends 8 of rotatable rods 9 that respectively extend in opposite directions transversely of the car. By rotating either of the rods 9 the coupler lock 3 may be brought to unlocked position, and in case the coupler is provided with knuckle opening mechanism the knuckle 2 may be caused to rotate to open position. This lock-actuating mechanism, which has been chosen for purposes of illustration merely, is fully described in the I. H. Milliken Patent No. 1,184,116, dated May 23, 1916.

The mechanism for actuating each of the rods 9 is identical, and, therefore, but one of these mechanisms has been illustrated. While it is preferred to use two sets of mechanism so that the operator while standing at either side of the car may unlock the coupler and shift it laterally in either direction, it is nevertheless to be understood that a single rod 9 and its actuating device may alone be employed, if desired.

100

105

110

At its outer end each operating rod 9 is movably connected to an operating lever 10, such connection being preferably formed by fashioning the adjacent end of the rod with jaws 11 which are adapted to receive the lever 10, and by passing a pivot bolt 12 through suitable openings in the jaws and lever. At its lower end the lever 10 may be, and preferably is, provided with a pedal or projection 13 which extends at an angle to the direction of length of the lever. This pedal affords convenient means whereby the trainman may actuate the lever 10 with his foot. The portion of the lever which is adjacent to the pedal 13 is preferably rounded so as to form a suitable operating handle 14, by which the trainman may conveniently operate the mechanism with his hand.

The upper end of the lever 10 is provided with a plurality of fulcrum points 15 either of which, as will be understood from an examination of Fig. 5, is adapted to coöperate with the fulcrum member 16 carried by the car. The fulcrum points 15 and the point of attachment of the rod 9 to the lever 10 are disposed in triangular relation, less force being thereby required to be applied at the handle to shift the coupler than would be required if but a single fulcrum point located on the vertical center line of the lever were employed. The fulcrum points 15 are preferably about two inches distant from the vertical center line of the lever, but they may be located at any reasonable distance therefrom.

In order that the operating lever 10 shall be always in practical engagement with the fulcrum member 16, it is preferred to provide the latter with a curved, rearwardly extending, projection 17 that enters an opening or loop 18 formed at the upper end of the lever and is interposed between the fulcrum points 15 of the lever. The lateral edges of the projection 17 are rounded, as at 19, to provide fulcra, or pivotal points, for the respective fulcrum points 15 of the lever 10. As shown in Fig. 5 the configuration of the opening 18 is such as to permit the operating lever to be rotated around either of the edges 19 of the projection 16. In the particular form and arrangement of parts shown in the drawings, the upper wall of the fulcrum member 16 is cut away, as at 20, to afford clearance for the upper end of the lever 10 during its rotation when operating to shift the coupler laterally when the coupler is unlocked. Brackets 21 are preferably employed to support the operating rods or members 9 from the car body in such manner that said rods may be capable of sliding, turning and swinging or oscillating freely. As shown in the drawings it is preferred to make such brackets integral with the corresponding fulcrum members 16 and 65 to provide each with a laterally opening

slot 22 through which the rod 9 may be introduced and withdrawn. A cotter 23 extending across this slot may be employed as a means for preventing the rod 9 from escaping from the bracket 21.

When the coupler is to be unlocked the trainman grasps the operating handle 14 of the lever 10 and pulls it forwardly. This movement of the operating lever causes a rotation of the adjacent rod 9 sufficient to unlock the coupler 1, or to cause the knuckle 2, if the latter is free to open, to be rotated to open position when the coupler is equipped with knuckle opening mechanism. This position of the lever is illustrated in dotted lines in Fig. 3. By now pulling or pushing upon the lever, as the necessary direction of movement of the coupler may require, the trainman may cause a corresponding pull or push to be transmitted to the coupler through the operating rod 9, thus causing the coupler 1 to be correspondingly shifted. As previously explained, the trainman may place his foot upon the pedal 13 and thus push upon the lever 10 instead of pushing it by hand.

When the lever 10 is actuated to cause a lateral shifting of the coupler in one direction, one of the fulcrum points 15 engages the corresponding fulcrum face 19 of the curved projection 17, and when the lever is rotated to cause the coupler to be shifted in the opposite direction, the other fulcrum point 15 and corresponding fulcrum face 19 coöperate. The lever 10, it will be perceived, is thus capable of rotation about three distinct axes.

Should it be desired to shift the coupler laterally in either direction without unlocking it, the trainman may merely push or pull upon it without moving it in a direction to cause a rotation of the rod 9 and consequent movement of the lock 3 to unlocked position.

I claim:

1. In mechanism of the character indicated, the combination with a coupler mounted on a railway car so as to be capable of moving laterally, of means for shifting said coupler laterally, said means involving a fulcrum member, and a lever having a plurality of fulcrum points either of which is adapted to coöperate with said fulcrum member, the fulcrum member being interposed between the fulcrum points of the lever.

2. In mechanism of the character indicated, the combination with a coupler mounted on a car so as to be capable of moving laterally, of means for shifting said coupler laterally in either direction, said means involving a lever having an operating handle and a plurality of fulcrum points, and means connecting said lever to said coupler, said fulcrum points and the

point of attachment of said connecting means to said lever being triangularly disposed, the fulcrum member being interposed between the fulcrum points of the lever.

3. In mechanism of the character indicated, the combination with a coupler mounted on a railway car so as to be capable of moving laterally, of means for unlocking said coupler and shifting it laterally, said means involving a lever which is adapted to be rotated about three distinct axes, and a fulcrum member interposed between two of the axial points of the lever.

4. In mechanism of the character indicated, the combination with a coupler mounted on a railway car so as to be capable of moving laterally, of means for shifting said coupler laterally, said means involving a fulcrum member affording a plurality of fulcra for an operating lever, and an operating lever adapted to fulcrum upon either of said fulcra, said operating lever having an opening, and said fulcrum member having a projection extending into said opening.

5. In mechanism of the character indicated, the combination with a coupler mounted on a railway car so as to be capable of moving laterally, said coupler involving a knuckle and a lock therefor, of means for moving said lock to unlocked position and for shifting said coupler laterally, said means involving a fulcrum member, a lever coöperating with said fulcrum member, and means operatively connecting said lever and coupler and adapted to actuate said coupler lock, said lever being rotatable in one direction to induce an unlocking movement of said lock, and being rotatable in another direction to effect a lateral shifting of said coupler, said shifting being effected independently of an unlocking movement of said lever.

6. In mechanism of the character indicated, the combination with a coupler mounted on a railway car, so as to be capable of moving laterally, said coupler involving a knuckle and a lock therefor, of means for moving said lock to unlocked position and for shifting said coupler laterally, said means involving a fulcrum member, a lever coöperating with said fulcrum member, and means operatively connecting said lever and coupler and adapted to actuate said coupler lock, said lever being movable in one direction to induce an unlocking movement of said lock, and being movable in another direction to effect a lateral shifting of the coupler, said lever and said fulcrum member being adapted to coöperate in all positions

of the parts, whereby the coupler may be shifted laterally either when it is locked or 65 when it is unlocked.

7. In mechanism of the character indicated, the combination with a coupler mounted on a railway car so as to be capable of moving laterally, of means for shifting said coupler laterally in either direction, said means involving a fulcrum member having a projection affording a plurality of fulcra, a lever having at its upper end an opening which is adapted to receive said projection, 75 and a rod operatively connected to said lever and coupler, said lever being adapted to engage and turn upon either of said fulcra of said projection, whereby the coupler may be shifted laterally in either direction by a corresponding rotation of said lever.

8. In mechanism of the character indicated, the combination with a coupler mounted on a railway car so as to be capable of moving laterally, of means for shifting 80 said coupler laterally in either direction, said means involving a fulcrum member mounted on the car body, a rotatable lever, and a rod operatively connected to said coupler and lever, one arm of said lever being adapted to engage said fulcrum member above said rod and the other arm of said lever being provided with a pedal extending at an angle to the direction of length of said lever.

9. In mechanism of the character indicated, the combination with a coupler which is mounted on a railway car so as to be capable of moving laterally, of means for shifting said coupler laterally, said means involving a lever, and a fulcrum member 100 affording a plurality of fulcra, said lever being adapted to coöperate with either of said fulcra, and said fulcra having curved faces forming pivotal points for said lever.

10. In mechanism of the character indicated, the combination with a coupler mounted on a railway car so as to be capable of moving laterally, said coupler involving a knuckle and a lock therefor, of means for moving said coupler to unlocked position 110 and for shifting said coupler laterally, said means involving a rotatable rod operatively connected to said lock and extending toward the side of the car, a lever pivotally connected to and adapted to actuate said rod, 115 and a fulcrum member with which said lever is adapted to coöperate, said fulcrum member having a curved projection, and said lever having an opening for the reception of said curved projection and being adapted 120 to rotate while in engagement with said projection.

In testimony whereof I affix my signature.

WILLIAM KELSO.
